(57) **ABSTRACT**

'HG07' is a hybrid dessert banana variety with a tall stature, is tolerant to Black Sigatoka, and produces high-quality fruit.

6 Drawing Sheets

1

Latin name of the genus and species of the plant claimed:
Musa acuminata.

Variety denomination: 'HG07'.

CROSS-REFERENCE TO RELATED APPLICATIONS

This application is co-pending with the following additional applications by the same inventor: "DESSERT BANANA PLANT NAMED 'SH-4199'" (patent application Ser. No. 18/469,772), "DESSERT BANANA PLANT NAMED 'WW01'" (patent application Ser. No. 18/469,766), "DESSERT BANANA PLANT NAMED 'NW02'" (patent application Ser. No. 18/469,776), and "DESSERT BANANA PLANT NAMED 'WH02'" (patent application Ser. No. 18/469,781). The plants of these applications, as well as the plant of the present application, were created in the banana breeding program of Applicant/Owner/Assignee, FHIA.

STATEMENT REGARDING FEDERALLY SPONSORED RESEARCH OR DEVELOPMENT

Not applicable.

BACKGROUND OF THE INVENTION

This invention relates to a new and distinctive hybrid banana variety named 'HG07'. This new hybrid variety was the result of a field cross performed in La Lima Cortés, Honduras, between 'HG' x 'HG' (Both unpatented). 'HG' is a triploid plant (AAA) susceptible to Black Sigatoka leaf spot disease and *Fusarium oxysporum* race 1, belonging to the Gros Michel group. 'HG' is a mutant of Gros Michel used in genetic improvement to generate tetraploid mothers; varieties of the Cavendish group replaced this variety due to

its susceptibility to fusariosis. In the 20th century, it was one of the world's most commercialized fruits due to its excellent taste and yield.

'HG07' is a tetraploid hybrid (AAAA) created for the genetic improvement of the Gros Michel banana group. This hybrid was selected in 2018 from several first-generation seedlings from the cross between 'HG' x 'HG'. It was chosen as a tetraploid hybrid maintaining the "Gros Michel" type stature and taste of its female parental line and producing bunches of 25 kilograms with fruits of the same quality as their parents. 'HG07' was asexually reproduced by corms in La Lima Cortés, Honduras. All plants and fruit run true to the initially selected plant and are identical in all aspects.

'HG07' is a selection of crosses made between plants of the "HG" variety, inheriting its flavor, cluster shape, and plant structure. The few differences between 'HG07' and its parents can be seen in the shape of the fruit, which is slightly smaller and has shorter fingers. Another important difference is the fertility when used as a mother; 'HG07' is more fertile than its 'HG' parents. The other characteristics are very similar between 'HG07' and its 'HG' parents.

When comparing 'HG07' with a commercial cultivar such as 'Grand Naine' or 'Williams', we can say that there are important characteristic differences such as: the size of the plant, which is superior in 'HG07'; the flavor of commercial varieties is simpler than that of 'HG07'; the commercial varieties and 'HG07' have equal susceptibility to diseases such as Black Sigatoka; and commercial varieties are resistant to *Fusarium oxysporum* f.sp. *cubense* Race 1, while 'HG07' is susceptible.

BRIEF SUMMARY OF THE INVENTION

'HG07' is a hybrid dessert banana variety with a tall stature, is tolerant to Black Sigatoka, and produces high-quality fruit.

BRIEF DESCRIPTION OF THE PHOTOGRAPHS

The figures describe the characteristics of the 'HG07' hybrid banana variety. The color shown in the photographs is as nearly accurate as reasonably possible in this type's color representation.

FIG. 1 shows the typical appearance of a plant at nine months old;

FIGS. 2A-B shows blotches at the petiole base (A) and a petiole canal leaf (B);

FIGS. 3A-C shows the shape of a leaf blade base (A) and leaf upper (B) and leaf lower (C) surfaces;

FIG. 4 shows typical suckers;

FIG. 5 shows a usual fruit bunch;

FIG. 6 shows a male bud;

FIGS. 7A-C shows bracts of a male bud;

FIG. 8A-B shows compound tepal (A) and free tepals (B) lobes;

FIG. 9A-B shows style shape (A) and ovary (B);

FIG. 10 shows a typical male flower;

FIG. 11 shows rowed ovules; and

FIG. 12 shows a typical second hand.

DETAILED BOTANICAL DESCRIPTION

The following is a detailed botanical description of the new variety 'HG07' at nine months old. The report is from plants located in La Lima, Cortés, Honduras, that were evaluated in 2023. The descriptions concord with the internationally standardized "Descriptors for Banana (Musa spp.)" elaborated by IPGRI/INIBAP/CIRAD, 1996, and The U.K.'s Royal Horticultural Society's (R.H.S.) Colour Chart, 2001. The 'HG07' plant and its fruit may differ slightly from the detailed descriptors shown below due to variations in cultural practices, soil types, and climatic conditions under which the variety may be cultivated.

TABLE 1

Botanical Description of 'HG07'	
Leaf habit	Intermediate
Dwarfism	Normal
Pseudostem height	≥3 (3.2) meters
Pseudostem aspect	Normal
Pseudostem color	Yellow-Green (N144C, RHS)
Pseudostem appearance	Shiny (not waxy)
The predominant underlying color of the pseudostem	Blue-Green (112D, RHS)
Pigmentation of the underlying pseudostem	Red (46A, RHS)
Sap color	Watery (White 155C RHS)
Wax-on leaf sheaths	Very Little or no visible sign of wax
Number of suckers	5
Development of suckers	Very good
Position of suckers	Close to parent (vertical growth)
Blotches at the petiole base	Extensive pigmentation
Blotches color	Brown (N200A, RHS)
Petiole canal leaf III	Wide with erect margins
Petiole margins	Winged and clasping the pseudostem
Wing type	Dry, short wings
Petiole margin color	Purple (77A, RHS)
Edge of petiole margin	Colourless (Without a color line along)
Petiole margin width	>1 cm
Leaf blade length	171 to 220 cm
Leaf blade width	71 to 80 cm
	40
	45
	50
	55
	60
	65
Botanical Description of 'HG07'	
Petiole length	≤50 cm
Color of the leaf's upper Surface	Green (137B, RHS)
Appearance of leaf upper surface	Shiny
Color of the leaf's lower surface	Yellow-Green (147B, RHS)
The appearance of the leaf's lower surface	Dull
Wax on leaves	Very Little or no visible sign of wax
The insertion point of the leaf blade on the petiole	Symmetric
The shape of the leaf blade base	Both sides rounded
Leaf corrugation	Even, smooth
Venation pattern	Single centralized
Color of midrib dorsal surface	Yellow-Green (144B, RHS)
Color of midrib ventral surface	Green-White (157A, RHS)
Color of cigar leaf dorsal surface	Green (139C, RHS)
Blotches on leaves of water suckers	Without blotches
Peduncle length	31-60 cm
Empty nodes on the peduncle	Two or more
Peduncle width	7-12 cm
Peduncle color	Yellow-Green (144A, RHS)
Peduncle hairiness	Slightly hairy
Bunch position	Hanging vertically
Bunch shape	Truncated cone shape
Bunch appearance	Compact
Flowers that form the fruit	Female
Fruits	Biseriate
Rachis type	Present and male buds may be degenerated or persistent.
Rachis position	Failing vertically
Rachis appearance	Bare
Male bud type	Normal (present)
Male bud shape	Intermediate
Male bud size	25-30 cm
Bract base shape	Large shoulder
Bract apex shape	Slightly Pointed
Bract imbrication	Old bracts overlap at the apex of the bud.
Color of the bract external face	Greyed-Purple (187A, RHS)
Color of the bract internal face	Greyed-Purple (185A, RHS)
Color of the bract apex	No tinted with yellow (the color is uniform until apex)
Color stripes on the bract	Without discolored lines (not ridges) on the external face
Bract scars on rachis	Very prominent
Fading of color on bract base	Color discontinuing towards the base.
Male bract shape	Ovate
Male bract lifting	Lifting two or more at a time
Bract behavior before falling	Revolute (Rolling)
Wax on the bract	Moderately waxy
Presence of grooves on the bract	Moderate
Male flower behavior	Falling before the bract
Compound tepal basic color	Green-White (157D, RHS)
Compound tepal pigmentation	Rust-colored spots
Lobe color of compound tepal	Yellow (7B, RHS)
Lobe development of compound tepal	Developed
Free tepal color	Translucent White
Free tepal shape	Oval
Free tepal appearance	Simple folding under the apex
Free tepal apex development	Developed
Free tepal apex shape	Triangular
Anther exertion	Exerted
Filament color	Greyed-White (156B, RHS)
Anther color	Green-White (157C, RHS)
Pollen sacs color	Greyed-Green (196D, RHS)
Pollen vitality	Abundant
Style basic color	Greyed-White (196D, RHS)
Pigmentation on style	Without pigmentation
Style exertion	Exerted
Style shape	Curved at the base
Stigma color	Yellow-Orange (20B, RHS)
Ovary shape	Arched
Ovary basic color	Green-White (157B, RHS)

TABLE 1-continued

TABLE 1-continued

Botanical Description of 'HG07'	
Ovary pigmentation	Very few or no visible signs of pigmentation
The dominant color of male flower	Green-White (157D, RHS)
Irregular flowers	Absent
Arrangement of ovules	Two rowed
Fruit position	Parallel to the stalk
Number of fruits observed on the mid-hand of the bunch	≥17, specifically between 120 and 140 fingers per bunch
Fruit length	≤15 cm (12 to 15 cm)
Fruit diameter	8 to 10 cm
Fruit shape (longitudinal curvature)	Curved (sharp curve)
Transverse section of fruit	Pronounced ridged
Fruit apex	Bottle-necked
Average weight of a fruit	150 g
Average weight of bunch of fruit	21 kg
Average number of bunches per plant	One
Remains of flower relicts at the fruit apex	Persistent style
Fruit pedicel length	11 to 20 mm
Fruit pedicel width	>10 mm

TABLE 1-continued

Botanical Description of 'HG07'	
5	Average fruit pedicel width 5 cm
	Pedicel surface Hairy
	Fusion of pedicel Very partially or no visible sign of fusion
	Immature fruit peel color Green (143C, RHS)
	Mature fruit peel color Yellow-Orange (16B, RHS)
	Fruit peel thickness ≥3 (3 to 5) mm
10	Adherence to the fruit peel Fruit peels easily
	Cracks in fruit peel Without Cracks
	Pulp in fruit With pulp
	Pulp color before maturity Yellow-Green (150D, RHS)
	Pulp color at maturity Yellow (13D, RHS)
	Fruits fall from hands. No finger drop
	Flesh texture Firm (hard texture)
15	Predominant taste Sweet (like Cavendish)
	Presence of seed with the source of pollen Without seeds

20 The invention claimed is:

1. A new and distinct variety of banana plant named 'HG07', substantially as illustrated and described herein.
